United States Patent Office

Des. 228,581

Patented Oct. 9, 1973

228,581

CARPET

Jon M. Blumenaus and Evan Armstrong, Jr., Dalton, Ga.,
assignors to World Carpets, Dalton, Ga.

Filed July 6, 1972, Ser. No. 269,399

Term of patent 14 years

Int. Cl. D6—04

U.S. Cl. D92—4

The single figure is a top plan view of a carpet showing our new design, portions of the configuration of the design being muted into the background, a complete unit being shown from left to right with the vertical boundaries set out by dash lines, the unit repeating in regular succession beyond the unit boundaries.

The single figure is a black and white illustration of our new, original and ornamental design.

We claim:

The ornamental design for a carpet, as shown.
